UNITED STATES PATENT OFFICE.

PHILIP H. BEVIER, OF NEW YORK, N. Y.

FIREPROOF ARCH.

1,112,756.

Specification of Letters Patent.

Patented Oct. 6, 1914.

Application filed June 11, 1908. Serial No. 437,807.

To all whom it may concern:

Be it known that I, PHILIP H. BEVIER, a citizen of the United States, residing in the city of New York, borough of Brooklyn, 5 county of Kings, and State of New York, have invented a certain new and useful Fireproof Arch, of which the following is a specification.

This invention is an arch for use in the 10 construction of fireproof buildings.

At the present time two methods are in use for setting the blocks or tiles of terra cotta arches; first, in narrow spans, say up to 6 or 8 feet, the arch blocks are set with 15 all joints bedded with mortar by brick layers using a trowel, and, second, in wide span arches, wherein metal reinforcements are used, the blocks are set in dry condition by unskilled laborers, the blocks being set 20 with ends tightly abutting, a wide joint, usually about 4 inches, being left between the sides of the block, into which joint is placed a plastic material, the latter being also put over the tops of the blocks. No allowance has heretofore been made in the 25 wide span arch for the compressive strength of the blocks themselves (although this is considerable), the entire dependence being placed upon the reinforced concrete construction, wherein the hollow tiles or blocks 30 serve simply as convenient forms for the purpose of molding the concrete ribs; said hollow tiles or blocks operating to support the wet slab of concrete material during its 35 installation, and serving, also, as a flat surface for the reception of the plaster material for the ceiling.

Experience has shown that hollow tiles or blocks, when set in a dry condition to form 40 an arch between two rigid surfaces, such as the parallel beams of a building, possess about one-half ($\frac{1}{2}$) the crushing strength as compared with similar blocks or tiles which are embedded in mortar. The reason for 45 such disproportionate load carrying capacity of dry set tiles or blocks results from the fact that the ends, or end faces, of the blocks are irregular in outline, and when the blocks are set end to end, their end faces engage at 50 their highest points only, instead of engaging throughout the height and width of the hollow blocks. Now, when said blocks are subjected to a certain load, the engaging high portions thereof crush or break down, 55 with the result that the block splits and

crushes, and is easily destroyed, beginning with such points of disintegration.

My invention permits narrow span arches to be set by unskilled labor, instead of by brick layers, and at a saving of one half the 60 cost of the labor of setting the blocks, and in wide span arches, while the blocks are set in the same manner as at present, very great strength is secured by utilizing the compressive strength of the tile. 65

The present invention overcomes these objections by providing a novel construction of mortar joint formed by and between the tiles or blocks, whereby said blocks or tiles of an arch are so united as to utilize the full compressive strength of the tiles or blocks. 70

My arch consists of hollow tiles or blocks each having its top and side walls provided with a continuous cut away portion, preferably at one end and in the form of a bevel, 75 although a bevel may be provided at each end of the tile. The edge of a beveled portion at one end of the tile, in one embodiment of the invention, is adapted to contact with an unbeveled flat face on an adjacent 80 tile when a row is laid in an arch. This relation of the tiles produces spaces between them, which spaces are filled with suitable plastic material for the purpose of uniting the tiles into a solid homogeneous structure. 85

My new construction possesses, among others, the following advantages:—The tiles may be set, by unskilled labor, in a dry condition to form an arch; the plastic material, such as mortar, may be poured into the 90 spaces, or otherwise deposited therein, subsequent to setting the tiles, this operation being performed easily and quickly; the strength of the arch does not depend solely upon the use of the plastic bonding material, 95 nor is it affected by the contact of the irregular end faces of the tiles, for the reason that the tiles are bound and united at their meeting end faces, along the sides and top, by an unbroken line of plastic material, whereby 100 the full compressive strength of the tiles is utilized; and provision is made for the employment of a metal reinforce of any preferred construction.

Another important feature of my arch is 105 a filler block at one or both ends of a row of tiles, said filler block being positioned between the end block and an adjoining metal beam. Said filler block is provided with ribs or other projections on that side which 110

faces the beam, thus spacing the surface of the block relative to the beam, whereby plastic material may be used to fill in the spaces, such plastic material serving to bind the 5 filler block to the beam, and also, as a medium for minimizing corrosion of the metal beam. Preferably, the filler block is provided with a bevel on its top and side edges, and this beveled part of the filler block engages with the flat end portion of an adjoining arch block, thus producing a space 10 for the reception of plastic bonding material.

In the accompanying drawings, I have 15 illustrated practical embodiments of the invention, but the constructions shown therein are to be understood as illustrative, only, and not as defining the limits of the invention.

20 Figure 1 is a side view of a tile arch, the blocks of which are constructed and assembled in accordance with this invention, a row of blocks being illustrated in coöperative relation to parallel beams. Fig. 2 is a plan view of one row of complete blocks 25 shown in coöperative relation to portions of two adjoining rows of blocks, the metal beams being shown in horizontal section. Fig. 3 is a horizontal section on the line 3—3 of Fig. 1. Fig. 4 is a vertical cross section on the line 4—4 of Fig. 1. Fig. 5 is an end view of one of the tiles or blocks. Fig. 6 is a perspective view on an enlarged scale 35 of one of the tiles or blocks, showing the beveled portions on the sides and the flat top of said tile. Fig. 7 is a sectional view illustrating a filler block positioned between a metal beam and an end block or "skewback" of a row of tiles. Fig. 8 is a plan, 40 with the metal beam in horizontal section, showing portions of three filler blocks in coöperative relation to a corresponding number of end tiles or "skewbacks" of an arch. Fig. 9 is a horizontal section through the 45 part shown in Fig. 8. Fig. 10 illustrates another form of tile embodying my invention adapted for use in connection with wide arches wherein it is desirable to use a metal reinforcement, and Fig. 11 is an end view 50 of one of the tiles or blocks in the construction of the arch shown in Fig. 10.

The example of the invention shown in Figs. 1, 2 and 3 of the drawings consists in an arch composed of five blocks or tiles, A, 55 B, C, D, and E, placed in a row between adjacent parallel beams or girders, F; but it will be understood that the number of blocks composing each row may be changed. The block, A, is the key-block of the arch, 60 and preferably, the ends of this key-block are inclined on diverging lines from the bottom upwardly. The end blocks, D, E, of the row are technically termed the "skewbacks," and, preferably, the blocks, B, C, 65 D, and E, are constructed in accordance

with this invention. Each block embodying my invention is cellular in construction substantially as shown in Figs. 5 and 6; that is to say, each block consists of a bottom, a, a top, b, parallel side walls, c, c', and intersecting webs, d, e, which form the cells that extend lengthwise of the block. The construction of the block, however, in so far as concerns the cellular features thereof, may be modified or changed as desired, for 75 the reason that my invention may be incorporated in non-cellular blocks, that is to say, blocks which are not provided with webs, such as, d, e, or either of them. Generally speaking, the blocks, B, C, D, E, are 80 provided with inclined faces at meeting end portions thereof; thus the blocks, B, C, have their end faces inclined on diverging lines so as to correspond to the end portions of the interposed key-block, A, whereas the 85 "skewbacks," D, E, are provided with an inclined face at one end and a vertical face at the other end, the vertical face of end blocks, D, E, being next to parallel beams, F.

90 One of the distinguishing features of my construction consists in the provision of a cut-away portion on one end face of each block, such as blocks, B, C, D, E. This cut-away portion is shown in Figs. 5 and 6, more particularly as a bevel, G, which is 95 provided on the top, b, and the side walls, c, c'; said bevel running continuously from the lower edge of one side wall, c, up to and across one edge of the top wall, d, and thence downwardly to the other lower edge of the 100 wall, c'. The bevel does not occupy or take up the thickness of the wall at the end portion of the block, but within the bevel is a bearing edge, g, the latter being flush with the end face of the bottom, a, and the webs, 105 d, e, provided the latter are embodied in the construction of the block. From this description it will be seen that each block is provided, preferably at one end, with a bevel around a bearing edge; said bevel being 110 clearly differentiated from the inclined end face of the block. As shown, the bevel is on one end face of each block, whereas the other end face of each block is flat, so that this flat end resembles the ordinary tiles or 115 blocks, but it is obvious that a bevel, G, may be provided on each end of the block or tiles.

The arch shown in Figs. 1, 2 and 3 does not embody the bevel, G, on the inclined ends of key-block, A, but unless filler blocks, 120 H, are used between the blocks, D, E, and the I-beams, F, as shown in Figs. 7, 8 and 9, said blocks, D, E, are provided with bevels, H², at the ends thereof next to beams, F.

125 Each block is provided with flanges, h, on the respective sides thereof, said flanges running lengthwise of the block and being in the plane of the bottom, a, thereof. Furthermore, the parallel side walls, c, c', are, 130

or may be, provided with the grooves, i^2 , but said grooves, i^2 , may be omitted, if desired.

In laying the blocks of a wide span, a temporary stage or platform is positioned below the beams, and the blocks, A, B, C, D, E, are placed, in a dry condition, on said stage and in proper alignment between the beams. It should be noted that blocks, D, E, are first placed in position, then blocks; B, C, and finally key-block, A, is inserted. The end portions of blocks, B, C, with their bevels, G, are in abutting engagement with inclined ends of key-block, A. The end portions of blocks, D, E, having bevels, G, are in engagement with non-beveled ends of blocks, B, C, respectively. In some forms of arches, the ends of the blocks are cut square, or at right angles to the length, while in other forms of arches, the ends of the blocks are inclined. I have elected to show the latter form of blocks (with inclined ends) in the drawings, but the invention may be used with blocks having squared ends. In the arch shown in Figs. 1, 2 and 3, end blocks, D, E, have bevels, H^2 , on the ends next to beams, F, as well as on the ends which abut blocks, B, C, but bevels, H^2 , may be omitted when filler blocks, H, shown in Figs. 7, 8 and 9, are placed between beams, F, and blocks, D, E. After laying one row of blocks, other rows are laid in like manner, and the flanges, h , of the blocks in adjoining rows engage with each other, as shown in Fig. 4, whereby the blocks in adjoining rows are spaced, as at i , relative to each other in the operation of laying the blocks, and the meeting flanges, h , close the spaces, i , between the adjacent tiles, at the bottom thereof.

The assembling of every two blocks in end-wise engagement, with the beveled portion, G, of one block next to a non-beveled end face of the adjacent blocks, provides a space, g^4 , at the abutting faces (see Figs. 1 and 2), which space extends, preferably, across the tops and down the side walls of the blocks. Said spaces, g^4 , are adapted to receive the plastic material, G', such as mortar or cement, and the spaces, i , are filled, also, with mortar or cement, I', whereby the tiles of each row are bound to each other by the material, G', and the adjoining rows of tiles by the material in the joints, I'.

It is to be observed that the tiles may be placed in position easily, quickly and by unskilled labor; that the plastic material may be poured on or otherwise deposited in the spaces, g^4 , i , between the tiles; and that the flanges, h , between the sides of the tiles and the engaging faces at the ends of the tiles preclude the loss of the plastic material by leakage at the bottom of the tiles.

Practical tests of an arch embodying this invention have shown that it possesses

greater strength and load carrying capacity than arches employing other forms of tiles. This is due, mainly, to the beveled end portions of the tiles receiving the bonding material, G', that operates to unite the tiles end to end, whereby irregularities in the abutting end faces of the tiles do not allow for lines of weakness, but on the contrary, the tiles are so united as to utilize the full compressive strength thereof.

Filler blocks, H, are each composed of a comparatively thin slab of fireproof material, each block being adapted for use between a beam and one end block or "skewback", D or E. It is preferred to provide means, such as the ribs, h' , on one face of the filler block for spacing it relative to the web of beam, F, thus producing intermediate spaces, h^2 , between beam, F, and block, H, which spaces are filled by plastic material, such as cement or mortar, whereby the filling of plastic material operates as a protective covering in minimizing corrosion of the metal beam. It is preferred, also, to provide each filler block with a bevel, h^3 , on that edge of the face which engages with the end of the end block or "skewback", and the space formed by said bevel, h^3 , receives a filling of plastic material, the latter uniting the filler block and "skewback" so as to increase the strength of the arch.

In case of wide arches, or arches having an increased span, it is preferred to employ blocks or tiles, B', having the side walls inclined at top and bottom at c^2 , c^3 , see Figs. 10 and 11. Said blocks have the same general structural features as the blocks heretofore described, but it is preferred to make the upper parts, c^2 , of the side walls of increased thickness as compared with the lower parts, c^3 , whereby the strength of the compressive portion of the tile is increased. An arch composed of rows of blocks, such as, B', is provided with double tapered spaces, i' , between the side walls of the blocks, see Fig. 10, and this space, i' , as well as the other spaces between the blocks, are filled with the plastic material; such material in the spaces, i' , forming a double key. Furthermore, the arch may be reinforced by metallic tension members, such as, J. The tension member may be composed of any suitable material, and said member may be dropped or inserted into the space, i , or i' , so as to lie close to the bottom of the tiles, said tension member being embedded in the bonding material between the tiles.

Having thus fully described the invention, what I claim as new and desire to secure by Letters Patent is:

1. In a fireproof arch, tiles assembled in wedging engagement into rows, the adjoining tiles of each row abutting at their bottom edges, thereby producing an arch the bottom of which is continuous, said adjoining

ing tiles having certain parts of their ends abutting and each tile being provided above the bottom edge and on the side walls and the top wall with a cut away portion positioned exteriorly of said abutting parts, whereby a mortar or cement receiving space is formed between each pair of abutting tiles.

2. In a fireproof arch, tiles assembled in wedging engagement into rows, the adjoining tiles of each row abutting at their bottom edges, whereby the resulting arch is provided with a bottom wall which is unbroken or continuous from side to side of the arch, each tile having at one end all the surfaces in substantially the same plane, the other end of each tile being provided with a cut away portion which is exteriorly to the abutting end surface, said cut away portions extending continuously along the top wall and the side walls but not at the bottom edge, whereby the adjoining tiles are assembled to produce a free or unobstructed mortar or cement receiving space exteriorly to the abutting end faces and above the engaging bottom edges thereof.

3. In a fireproof arch, tiles assembled in wedging engagement into rows, the adjoining tiles of each row abutting at their bottom edges lengthwise of the row, thereby producing a continuous tile surface at the bottom of the arch, each tile having at one end an abutting surface all the parts of which are in substantially the same plane and the other end of said tile having a surface some of which is cut away and other parts of which surface are positioned for engagement with the abutting surface of the next tile, said cut away surface of the tile extending continuously along the top wall and the side walls of each tile but not along the bottom edge thereof, whereby a mortar receiving space is provided between each pair of tiles exteriorly to the abutting surfaces thereof and above the abutting bottom edges of said tiles.

4. In a fireproof arch, tiles assembled in wedging engagement into rows, the adjoining tiles of each row abutting at their bottom edges lengthwise of the row, thereby producing a continuous tile surface at the bottom of the arch, each tile having on the side and top walls a beveled surface positioned exteriorly to an abutting surface on the end of said tile, whereby two adjoining tiles are positioned in abutting engagement at their ends and a mortar or cement receiving space is provided between a part only of the ends of said tiles, which space extends continuously along the top and side walls but is interrupted at the bottom end edges of the tiles, each row of tiles being spaced relative to an adjoining row or rows of tiles, and bonds of mortar or cement filling the spaces between adjoining rows of tiles so as to result in transverse concrete ribs and

said bonds of mortar or cement filling the spaces exteriorly to the abutting end faces of each pair of adjacent tiles.

5. In a fireproof arch, a series of tiles assembled into rows, the adjoining rows being spaced apart to produce a substantially wide cement-receiving space between said rows, the adjoining tiles of each row being positioned for their ends to abut, the sides and top of each tile, at one end thereof, being beveled exteriorly of said abutting end face, whereby a cement-receiving space is provided next to the abutting faces of two adjoining tiles, said spaces extending continuously across the top and along two sides of each tile and said spaces being in communication with the substantially wide spaces between adjoining rows of tiles, the bottom edges of adjoining tiles in each row being unbroken at their ends and contacting with each other, thereby producing a bottom wall or under surface which is continuous from side to side of the arch.

6. In a fireproof arch, a supporting beam, a row of tiles, and a filler block positioned intermediate the beam and an end tile of said row, said filler block being provided on its side next to the end tile with a face abutting said end tile and with a cut away portion exteriorly of the abutting surfaces, said filler block being provided on the surface opposing the beam with projections which contact with said beam and operate to produce spaces between the filler block and the beam, said spaces being filled with bonding material.

7. In a fireproof arch, a supporting beam, a row of tiles, and a filler block positioned intermediate the beam and an end tile of said row, said filler block being provided on its side next to the beam with a series of ribs which project beyond the normal face of the block, said ribs being in contact with the beam and operating to space the face of the block with relation to the beam, said spaces being filled with bonding material.

8. A tile having at one end an abutting surface in the same plane as the bottom edge of said end and a cut away portion exteriorly of the abutting surface and extending along the sides and top of said end, the bottom edge of said tile being unbroken, and the other end of the tile having its top, bottom and sides in the same plane.

9. A hollow tile having webs internally thereof and provided at one end with an abutting surface in the same plane as the bottom edge of said end and a cut away portion exteriorly of the abutting surface and extending along the sides and top of said end, and a second tile having an end face in the same plane with the bottom, sides and top, said end face of the second block being in abutting engagement with the abutting surface of the first tile, whereby a

mortar receiving space is provided around the sides and across the top of the abutting faces of adjoining tiles, the bottom edges of said tiles being unbroken and in contact, thereby producing a continuous bottom wall or under surface on the tiles.

10. A tile having an unbroken bottom edge at one end, and an abutting end face in substantially the same plane as said bottom end edge of the tile, the sides and top of said tile having above the unbroken end edge certain inclined cut away portions positioned exteriorly of said abutting end face.

11. A tile having at one of its ends an abutting face on its base, sides and top, a bevel exterior to said abutting face and extending along the sides and top of said end, the bevels on the side terminating above the base, and flanges projecting from the respective sides of the tiles and lying in the plane of the base thereof.

12. In a fireproof arch, rows of tiles separated from each other in sidewise relation by spaces extending lengthwise of the arch, the tiles of each row abutting at their end faces and each tile being provided with a bevel exterior of the abutting end face, thereby producing between the abutting ends of adjoining tiles a space which communicates with the lengthwise extending spaces between the rows, and mortar bonds filling the spaces between the rows and also filling the spaces adjacent to the abutting faces between the sides and top of the pairs of adjoining tiles.

In testimony whereof I have signed my name to this specification in the presence of two subscribing witnesses.

PHILIP H. BEVIER.
